UNITED STATES PATENT OFFICE

146,465

DESIGN FOR A TOY AUTOMOBILE

Edmond R. Doak and Nelson E. Grace, Los Angeles, Calif., assignors to Doak Aircraft Co., Inc., Torrance, Calif., a corporation of California

Application June 18, 1945, Serial No. 120,186

Term of patent 14 years

(Cl. D34—15)

To all whom it may concern:

Be it known that we, Edmond R. Doak and Nelson E. Grace, citizens of the United States, residing at Los Angeles, in the county of Los Angeles, State of California, have invented a new, original, and ornamental Design for Toy Automobile, of which the following is a specification, reference being had to the accompanying drawings, forming a part thereof.

The ornamental design for a shuttlecock, as mobile showing our new design.

Figure 2 is a top plan view of the toy automobile shown in Figure 1.

Figure 3 is a rear perspective view of the toy automobile shown in Figure 1.

Figure 4 is a front elevation of the toy automobile shown in Figure 1.

We claim:

The ornamental design for a toy automobile, as shown.

EDMOND R. DOAK.
NELSON E. GRACE.
